Primary Examiner — Susan Bennett Hattan*Assistant Examiner* — Leanne Was(74) Attorney, Agent, or Firm — Cynthia R. Miller(57) CLAIM

The ornamental design for a fragrance bottle, as shown and described.

DESCRIPTION

FIG. 1 is a top, front and right side perspective view of my new design for a fragrance bottle;

FIG. 2 is a front elevation view of the fragrance bottle shown in FIG. 1, the rear elevation view being identical thereto;

FIG. 3 is a right side elevation view of the fragrance bottle shown in FIG. 1, the left side elevation view being identical thereto;

FIG. 4 is a top plan view of the fragrance bottle shown in FIG. 1; and,

FIG. 5 is a bottom plan view of the fragrance bottle shown in FIG. 1.

The broken lines depict portions of the fragrance bottle that form no part of the claimed design.
